UNITED STATES PATENT AND TRADEMARK OFFICE
CERTIFICATE OF CORRECTION

PATENT NO. : Des. 530,147 S
APPLICATION NO. : 29/238411
DATED : October 17, 2006
INVENTOR(S) : M. Schmidt

It is certified that error appears in the above-identified patent and that said Letters Patent is hereby corrected as shown below:

The title page showing the illustrative figure should be deleted and substitute with the attached title page.

The drawing sheet, consisting of Fig. 1 and 2, should be deleted and replaced with drawing sheet, consisting of Fig. 1 and 2, as shown on the attached page.

Signed and Sealed this

Sixteenth Day of October, 2007
